United States Patent Office

Des. 192,671
Patented Apr. 24, 1962

192,671

HEATING TRAY

Lawrence Lerner, White Plains, N.Y., assignor to Michael Saphier Associates, Inc., New York, N.Y., a corporation

Filed May 29, 1961, Ser. No. 65,373

Term of patent 3½ years

(Cl. D81—10)

FIG. 1

FIG. 2

FIG. 3

FIG. 4

FIG. 1 is a perspective view of a heating tray showing my new design;

FIG. 2 is an end elevational view thereof;

FIG. 3 is a side elevational view thereof; and

FIG. 4 is a top plan view thereof.

I claim:

The ornamental design for a heating tray, substantially as shown.
